(57) **CLAIM**

The ornamental design for leadframe matrix for a surface mount package, as shown and described.

DESCRIPTION

FIG. 1 is a top plan view of a portion of a leadframe matrix for a surface mount package showing my new design; FIG. 2 is a top plan view of a single surface mount package shown at a larger scale for clarity of illustration; and, FIG. 3 is a perspective view of FIG. 1.

The leadframe matrix for a surface mount package is shown broken away in FIGS. 1 and 3 of the drawing to indicate indeterminant length, it being understood that it has a uniform shape and appearance throughout its length.
